UNITED STATES PATENT OFFICE.

DANIEL J. CABLE, OF PITTSBURGH, PENNSYLVANIA.

COVER FOR PITCHERS.

1,246,390.

Specification of Letters Patent. Patented Nov. 13, 1917.

Application filed October 21, 1915. Serial No. 57,121.

To all whom it may concern:

Be it known that I, DANIEL J. CABLE, a resident of Pittsburgh, in the county of Allegheny and State of Pennsylvania, have 5 invented a new and useful Improvement in Covers for Pitchers, of which the following is a specification.

This invention relates to detachable covers for pitchers, jugs or other liquid holding 10 receptacles. The object of the invention is to provide an improved detachable cover of very simple construction, so that it can be made and sold at low cost and is not liable to get out of order, and one which can be 15 easily manipulated and is readily attached to or detached from the pitcher or jug.

Further objects of the invention are in part obvious and in part will appear more in detail hereinafter.

20 In the drawings, which represent one embodiment of the invention, Figure 1 is a side elevation, partly in section, showing the detachable cover applied to a pitcher; Fig. 2 is a plan view of the detachable cover;

25 Fig. 3 is a detail perspective view of one of the cover members; and Fig. 4 is a detail cross sectional view on the line 4—4, Fig. 1.

In the drawings, the detachable cover is shown applied to a pitcher or jug 1, which 30 may be of any suitable shape, form or configuration, it being of course understood that the shape or outline of the cover will correspond with the particular form of pitcher for which it is intended. Said 35 pitcher is provided with the usual pouring lip 2 and handle 3.

The cover comprises essentially two members, to wit, a fixed member 4, which is stationary on the pitcher, and a member 5 40 movable relatively thereto, which covers the pitcher top and protects its contents from dirt, dust and other foreign matter. The fixed member 4 is pressed, stamped or otherwise formed of sheet metal, having a substantially straight outer portion 6 lying on 45 the outer surface of the pitcher wall just above the handle 3, and which may be provided with a central slot in its lower end, shown as a V-shaped opening, forming two 50 depending tongues 7 lying on opposite sides of the handle 3 and preventing the stationary member from moving laterally on the wall of the pitcher. The upper end of the member 4 is bent or folded into a loop 55 or hook 8 which embraces the upper edge of

the pitcher wall and by the resiliency of the metal frictionally holds the member 4 substantially immovable upon the pitcher. This construction enables the cover to be readily attached to the pitcher by merely pressing 60 its hook-shaped member down over the pitcher wall or readily withdrawn therefrom.

The movable member 5 is arranged to form a substantially complete seal around 65 the edges of the top opening of the pitcher and is shown as provided with a peripheral depending flange or rim 9, which closely hugs the wall of the pitcher, so as to close up all cracks or crevices and produce a 70 dust-tight joint. At its rear edge, just above the handle 3, the member 5 is extended outwardly and downwardly to form a curved handle or finger hold 10, which is conveniently adjacent to the handle 3, so that the 75 movable member of the cover may be readily manipulated by the thumb in its usual position for opening the cover to enable the contents of the pitcher to be poured.

The stationary and movable members of 80 the cover are connected by a simple form of hinge whose parts are preferably integral portions of said two members, so that the entire cover comprises only said members and requires no pintle, springs, wires or 85 other similar devices. As shown, the stationary member 4 is provided with two outwardly extending ears 11 which preferably lie below the upper end of the hook or loop 8, so that the axis of the hinge is below the 90 upper edge of the pitcher wall, whereby the cover moves upwardly and outwardly when turned upon its hinge. The movable member 5 is also provided with two ears 12, which preferably depend from the rearwardly extending handle member 10. Suitable interlocking hinge connections are provided on these two pairs of ears, the ears of one pair being preferably provided with projections which engage depressions or openings in the ears of the other pair. As illustrated, the ears of one pair, such as the ears 12 of the cover, are punched or pressed to provide teats or projections 13, which extend inwardly toward each other and engage 100 openings in the ears 11 of the stationary member 4. The resiliency of the metal is sufficient to enable the ears of the stationary member 4 to be sprung in between the ears 105 of the movable member 5 to enable the pro- 110

jections 13 to be engaged with their openings or depressions for assembling the two parts of the cover.

In its closed position, as indicated in Fig. 1, the inner face of the movable cover member 5 rests upon and is supported by the upper end of the loop or bend 8 of the stationary member 4, and also rests upon the periphery of the wall of the pitcher. This support relieves the hinge parts of strain in a vertical direction, while strain in a lateral direction is prevented by the engagement of the flange of the cover with the pitcher wall and the tongues 7 with the handle 3.

This cover can be readily manufactured by simple stamping and pressing operations and is easily assembled by merely pressing the parts together. It can be applied readily to any form of pitcher and is conveniently manipulated by the thumb or finger in the usual position of the hand when holding the pitcher.

What I claim is:

1. A detachable cover for pitchers or jugs, comprising a bent sheet metal member arranged to hook over the edge of a pitcher and provided with a pair of outwardly extending ears, a movable cover member having an outwardly extending sheet metal handle member provided with a pair of ears, and projections on the ears of one of said pairs arranged to resiliently engage openings or depressions in the ears of the other

pair and forming a hinge connection therebetween.

35

2. A detachable cover for pitchers or jugs, comprising a bent sheet metal member arranged to hook over the edge of a pitcher and provided with a pair of outwardly extending ears, a movable cover member having an outwardly extending handle member of resilient material provided with a pair of ears, and projections on the ears of said movable cover member arranged to engage openings in the ears of the other member and forming a hinge connection therebetween.

40

3. A detachable cover for pitchers or jugs, comprising a bent sheet metal member arranged to hook over the edge of a pitcher and retained by friction thereon, said member being provided below the upper edge of said pitcher with a pair of outwardly extending ears, a cover having an outwardly extending handle member, a pair of depending ears on said handle member, and projections on the ears of one of said pairs arranged to engage openings or depressions in the ears of the other pair and forming a hinge connection therebetween.

45

In testimony whereof, I have hereunto set my hand.

DANIEL J. CABLE.
